UNITED STATES PATENT OFFICE.

DELOS E. HAMMER, OF WASHINGTON, DISTRICT OF COLUMBIA.

RAILWAY-CROSSING.

1,261,519.

Specification of Letters Patent.

Patented Apr. 2, 1918.

Application filed December 13, 1917. Serial No. 206,985.

To all whom it may concern:

Be it known that I, DELOS E. HAMMER, a citizen of the United States, residing at Washington, in the District of Columbia, have invented new and useful Improvements 5 in Railway-Crossings, of which the following is a specification.

This invention relates to railway crossings, the broad object in view being to eliminate the gaps in the rails at the points of intersection of the rails of a railway crossing, which gaps ordinarily provide for the passage of the wheel flanges. By means of the construction hereinafter described, the 10 rails of the tracks in both directions are rendered in effect continuous or unbroken, such gaps being eliminated.

The construction involves the use of small turn tables at the intersecting points of the 15 rails where they cross each other, combined with novel means for simultaneously operating said turn tables, each of which carries a rail section, such section of the rail being adapted to be brought into alinement with 20 the rail, along which a car or a train is moving. The turn tables are automatically operated by tripping means and connections which are in turn actuated by contact with 25 the wheel flanges. As the tripping mechanism is depressed by a car moving in one direction, the tripping mechanism of the cross track is set in position to be operated by a car moving along the cross track when 30 it approaches the crossing, the entire mechanism being thus automatic.

A further object of the invention is to adapt the mechanism to an under-ground current system, so as to provide ample clearance for the current collector or shoe, which 35 extends below the surface of the roadway, for contact with the electrical conductor.

With the above and other objects in view, the invention consists in the novel construction, combination and arrangement of parts, 40 as herein described, illustrated and claimed.

In the accompanying drawings,

Figure 1 is a plan view of a railroad crossing, illustrating the present invention.

Fig. 2 is a vertical section on the line 45 2—2 of Fig. 1.

Fig. 3 is a plan view similar to Fig. 1, showing the system as adapted for an under-ground current railway.

Fig. 4 is a vertical section on the line 50 4—4 of Fig. 3.

Fig. 5 is a vertical cross section on the line 5—5 of Fig. 3.

Fig. 6 is a detail view of one of the diagonal connecting rods.

Fig. 7 is a plan view, showing the mechanism applied to a double track crossing. 60

Fig. 8 is a view similar to Fig. 2 showing another arrangement of the turn table operating means.

Referring to the drawings, A—A represent the rails of one track, and B—B the rails of another track crossing the first named track. At each point of intersection between the rails A and B, a turn table 1 is mounted, the same being adapted to turn 70 on a vertical axis. Each turn table carries a rail section a which may form either a continuation of the adjacent rail A or the adjacent rail B, the extremities of the short rail section a being adapted to abut against 75 or lie in close proximity to the adjacent extremities of either the rail A or the rail B, thereby leaving no gap or space between the extremities thereof, and enabling the wheels of a car to pass along the track without the usual bounding and consequent injury to the road bed. 80

In connection with each turn table, I employ operating means controlled by the advance wheels of the car or locomotive as the 85 case may be. Said means comprises in connection with each turn table, a rock shaft 2 which extends under the rails and entirely across the track. Extending upwardly from each rock shaft 2 are arms 3 arranged closely 90 adjacent to the inner sides of the rails A and B. Pivotedly connected to the upper extremity of each arm 3 is an inclined trip rail 4, adapted to be pressed downwardly by contact with the periphery of the flange 95 of one of the car wheels. The lower end of the inclined trip rail 4 has a projecting pin or lug 5 which slides along a horizontal guide way 6 in order to allow the arm 3 to swing downwardly. Extending from 100 each of the arms 3 to the adjacent turn table 1 is a connecting rod 7 connected to the arm 3 by a pivot 8 and connected pivotally to the adjacent turn table as shown at 9. As shown in Fig. 1, each turn table has 105 connected thereto two of such connecting rods 7, one leading to a rock shaft 2 of one track and the other leading to a rock shaft of the cross track. Under the arrangement just described, it will be seen that when a car 110

or a train approaches the crossing on track A, for example, the arms 3 of both rock shafts of said track at opposite sides of the crossing, are moved downwardly thereby shifting the short rail sections α into line with the rails A. At the same time, the rock shafts 2 of the other cross track B are moved to a substantially upright position, where they are ready to be operated by a car or train passing along the track B after the car or train has passed the crossing on the track A.

In applying the system to a road bed employing an under-ground electrical conductor, in order to provide for ample clearance for the shoe or current collector, I utilize the construction shown in Figs. 3 to 6 inclusive. In such a case, each rock shaft 2' will be arranged in the bottom of the subway and journaled at its opposite ends in bearings 10. The shaft 2' is provided with downwardly extending arms 11 to which are pivotally attached, connecting rods 12, the latter extending upwardly above the ground, where they are connected to arms 3' corresponding with the arms 3 of Fig. 2 and having attached thereto, the inclined trip rails 4'. From each rock shaft 2', connecting rods 7' extend to a pair of turn tables 1', each carrying a short rail section α' corresponding with the rail section α of Fig. 1. Extending diagonally between the intersecting portions of the rails A and B and connecting diagonal opposite turn tables 1 is a trussed connecting rod 13, comprising two arms 14 each shown as constructed of downwardly diverging rods 15 and 16, the rods 16 crossing each other and being united at 17, and the arms being further connected by a bottom brace 18. This forms a light, strong connecting rod. Two of such connecting rods are employed as shown in the drawings and they provide an additional factor of safety to prevent putting the mechanism out of order in case one of the other connecting rods 7 or 7' should become broken for any reason. Of course, each diagonal connecting rod 14 is pivotally connected at its opposite extremities to two diagonally opposite turn tables.

In Fig. 7, I have illustrated the system as applied to a double track road of the surface character shown in Fig. 1; it being, of course, understood, that the system may be equally well applied to a double track crossing by utilizing the construction shown in Figs. 3 to 6 inclusive. Under the arrangement shown in Fig. 7, the diagonal connecting rods 14 may connect with more than two turn tables as long as said turn

tables are arranged in line with each other. A turn table 1 will, of course, be employed at every point where the rails intersect. Each of the outer turn tables will be directly operated by one of the connecting rods 7 as 65 in the preceding views.

Instead of employing a single arm 3 as shown in Fig. 2, an additional arm 19 may be employed as shown in Fig. 8, the arm 19 being of the same length as the arm 3 and 70 being pivotally mounted at 20. A horizontal auxiliary rail 21 is pivotally connected at one end to the arm 3 and is pivotally connected at its opposite end to the arm 19. The rail 21 always lies below the surface 75 of the railway rail α , and is always maintained in a horizontal position. The flange of the car wheel rides upwardly on the inclined rail 4 and then travels throughout the length of the auxiliary horizontal rail 21, 80 thus insuring the proper turning movement for the turn table connected therewith.

I claim:

1. In a railway crossing, the combination with the intersecting rails, of a turn table 85 located at each point of intersection of the rails, a short rail section carried by said turn table and adapted to be turned into line with either adjacent rail, an inclined trip rail adjacent to the inner face of each track 90 rail, a pivoted arm to which one end of said trip rail is attached, a rock shaft located adjacent to the bottom of a subway between the track rails, arms projecting from said rock shaft, link rods connecting the first 95 and second named arms, and other connecting rods extending from the second named arms to the adjacent turn tables.

2. In a railway crossing, the combination with the intersecting rails, of a turn table 100 located at each point of intersection of the rails, a short rail section carried by said turn table and adapted to be turned into line with either adjacent rail, an inclined trip rail adjacent to the inner face of each 105 track rail, a pivoted arm to which one end of said trip rail is attached, a rock shaft located adjacent to the bottom of a subway between the track rails, arms projecting from said rock shaft, link rods connecting 110 the first and second named arms, other connecting rods extending from the second named arms to the adjacent turn tables, and diagonal connecting rods pivotally attached to diagonally opposite turn tables, each of 115 the last named connecting rods being centrally depressed.

In testimony whereof I affix my signature.

DELOS E. HAMMER.
